Cyril Bencraft Joly, New Close Cottage, Sleepers Hill,
Winchester, England

Filed Dec. 26, 1967, Ser. No. 9,920

Claims priority, application Great Britain June 26, 1967

Term of patent 3½ years

Int. Cl. D23—04; D6—01

U.S. Cl. D5—2

FIGURE 1 is a front perspective view of a portable ventilator for attachment to a bed with arms extended, FIGURE 2 is a top plan view thereof, and FIGURE 3 is a rear elevation thereof, but with the arms retracted.

I claim:

The ornamental design for a portable ventilator for attachment to a bed, as shown.
